UNITED STATES PATENT OFFICE.

CHARLES J. AHRENFELDT, OF NEW YORK, N. Y.

DESIGN FOR A POT.

SPECIFICATION forming part of Design No. 30,523, dated April 11, 1899.

Application filed January 11, 1899. Serial No. 701,890. Term of patent 3¹ years.

To all whom it may concern:

Be it known that I, CHARLES J. AHRENFELDT, a citizen of the United States, residing in the city of New York, county of New York, 5 and State of New York, have invented and produced a new and original Design for a Pot, of which the following is a specification, reference being had to the accompanying drawings, forming a part hereof, like letters referring to like parts in each figure of the same.

In the said drawings, Figure 1 is a side view of a pot embodying my design. Fig. 2 is a vertical section of the same on the line 3 3 of Fig. 3. Fig. 3 is a plan view of said pot.

15 The brim A of the pot has a series of indentations B in its periphery, giving it a wave-like appearance, with three small waves and one large wave alternated. Running around the inside of the brim is an annular ledge C, 20 upon which the stepped lower edge of the cover D rests. Beginning at each indentation in the brim and running down the sides of the pot to a point near the base are a series of vertical furrows E. The base F projects 25 from the bottom and is of like contour to the brim A.

On either side of the pot, just above the base, is an ornament, which consists of a central panel G, of three vertical divisions bordered on either side by an ornament H, which 30 resembles a C, with a stem bearing leafed and floral ornaments I proceeding from the upper part of the C.

The spout J is provided at its front part

with a like ornament K and has a series of 35 four furrows L running up from its base on either side.

The handle M, projecting from the bulged portion on the side opposite the spout, is made to resemble a number of lily-leaves bound together and joined to a curled knob N at the upper end.

The cover D is provided with four sets of 45 three radial ridges P, beginning abruptly near the outer boundary of its upper surface and tapering off as they approach the handle Q, at the center thereof, until they merge in the surface of the cover.

The handle Q is of oval form, provided with 50 leafed ornaments, and has a depressed portion on its upper side at the center. On either side of the handle is a pair of small fillet-like ornaments R, and a little farther removed therefrom, on either side, is a small ornament S, which consists of a central panel with ar- 55 besques on either side. A similar ornament S' is found between either end of the handle and the edge of the cover.

What I claim is—

The design for a pot herein shown and de- 60 scribed.

Signed at the city of New York this 4th day of January, 1899.

CHARLES J. AHRENFELDT.
